UNITED STATES PATENT OFFICE.

JESSIE M. BELL, OF TACOMA, WASHINGTON.

DESIGN FOR A DOLL.

Application filed August 10, 1926. Serial No. 18,681. Term of patent 14 years.

To all whom it may concern:

Be it known that I, JESSIE M. BELL, a citizen of the United States, residing at Tacoma, in the county of Pierce, State of Washington, have invented a new, original, and ornamental Design for Dolls, of which the following is a specification, reference being had to the accompanying drawing, forming part thereof.

The figure is a perspective view of a doll, showing my new design.

I claim:

The ornamental design for a doll, as shown.

JESSIE M. BELL.
